UNITED STATES PATENT OFFICE.

CHARLES EDWARD KIMBALL, OF CHATTANOOGA, TENNESSEE.

SKEIN-DYEING MACHINE.

Application filed November 15, 1927. Serial No. 233,422.

The invention relates to improvements in dyeing machines and more particularly to a skein dyeing machine of the reciprocating type.

An object of the invention is to provide novel means for dyeing skein yarn on rolls while completely submerged in a tank.

Another object is to provide means for oscillating the yarn support in the dye liquor in the tank in an up and down motion, the yarn being completely submerged during such motion. Means are provided as an object of the invention to intermittently shift the position of the yarn on the rolls for each stroke up and down of the yarn support.

A further object is to render the supporting frames interchangeable with regard to the tanks, thereby permitting a continuous process of dyeing.

Other objects of the invention will appear as the description proceeds and from the drawings and claims.

The invention consists in the features, combination and arrangement of parts hereinafter set forth and particularly pointed out in the claims.

In the accompanying drawings

Figure 1 is a front elevation partly in section of the dyeing machine and tank.

Fig. 2 is a sectional elevation of Fig. 1.

Fig. 3 is a view of the ratchet mechanism for intermittently driving the rolls. Fig. 3^a is an end view of Fig. 3.

Figs. 4 and 4^a are views of the guide T.

Referring to the drawings, A represents a tank or vat constructed of wood which may be metal lined to render it suitable for the resistance to such acids as it might come in contact with. The rectangular tank or vat A is provided at its ends with oppositely disposed and aligned uprights or bearing supporting columns C.

Bearings C' are provided at the top of the columns for receiving the ends of a shaft Q upon which shaft the entire yarn supporting frame B is hung.

The basket or frame B is preferably constructed of Monel metal, or other acid resisting metal and is rectangular in structure with top and bottom rails, a and b which support bearings c which in turn support

bottom or lower rolls D and upper rolls E, also constructed of acid resisting metal or wood. 55

The rolls D and E each consist of a tubular metal shaft d with a metal disc e at each end and metal slats f connecting the discs. The top rolls E are constructed in the same way as the bottom rolls except that the driven end g of the rolls has a tapered square projection h for receiving the driver k.

An inverted V-shaped truss m is formed at each end of the frame B and at the apex 65 of each truss a hanger n is pivoted. The upper ends of the hangers n are connected with eccentrics p, one eccentric being adjacent each end of the shaft Q.

The shaft Q rests in the bearings C' and 70 is rotated by any suitable means such as a gear wheel q which is connected through reduction gearing r with motor s mounted on a bracket attached to the tank. As the shaft Q is rotated an oscillating up and down motion is imparted by the eccentrics to the yarn carrying frame.

A stationary rod L is hung from shaft Q by means of sleeve t at its upper end. At 75 its lower end rod L carries a cross-head O which has a screw threaded connection therewith. Links N pivotally connected to opposite sides of cross-head O are pivotally connected at their lower ends to rods J which are aligned but are adapted to move in opposite directions upon relative vertical movement between the cross-head and frame. 80

Rods J pivotally carry depending pawl members I at spaced intervals along their length corresponding to the spacing between the rolls. The pawl members I each have a yieldable spring pressed pawl k² at their lower ends adapted to cooperate with teeth k' on drive wheels k to turn rolls E. 85

The pawl members I have openings 4 and 90 are pivotally received on drive wheels k in rear of teeth k' as shown at 5 in Fig. 3, and when swung in one direction will turn drive wheels k by means of pawls k² and when 95 swung in the opposite direction will move freely about drive wheels k with pawls k² slipping over the teeth k'. Drive wheels k are secured on the tapered square projection h on each of the upper rolls E. 100

As the shaft Q is rotated the eccentrics cause the frame to be oscillated up and down which produces relative movement between stationary rod L and the frame and causes the rods J through links N to move laterally relative to the frame and to cause pawl members I, the pawls k^2 of which are in engagement with teeth k' , to turn the rolls E thus moving the yarn for a short distance.

10 A guide P is secured to the truss m adjacent the rod L and receives the rod L to guide the frame in its reciprocating motion relative thereto. A lift frame S is mounted on the shaft Q to rotatably receive the same.

15 The skeins or hanks of yarn are placed one on each roll E and extend down into the dye-liquor and support corresponding rolls D. The rolls D are kept in place by having their stub ended shafts d in engagement with 20 slotted bearings c, these bearings being of sufficient length to accommodate different lengths of skein or hank yarn.

Guard rods K are provided to prevent the 25 yarn from getting over too near the end of the roll. M is a steam coil in the bottom of the tank.

As the shaft Q is rotated, the eccentrics cause the frame to reciprocate up and down on guides T at either end of the tank, the 30 tank being of sufficient depth to keep the skein or hank completely submerged during the process. Upon each reciprocation of the frame relative vertical motion takes place between the frame and rod L, causing movement of links N and rods J to operate the pawls and ratchets causing the rolls E to 35 rotate for a part of a turn. This motion is transmitted to rolls D and the whole hank or skein shifts position when the roll E turns.

40 The frame or basket is interchangeable with other tanks of like dimensions by simply lifting the frame out of the tank, and moving it to the next tank by means of a trolley and setting it down over the guides T and causing the gear on the end of the drive shaft Q to mesh with a pinion of the reduction gearing. In this way a continuous 45 process is permitted by transferring the basket and rolls from tank to tank while loaded with skein, for boiling out, degumming, dyeing, rinsing or softening.

50 Figs. 4 and 4^a show the spaced apart angle iron construction of the part 1 of the guide T which is secured to the tank by plates 2. Cooperating angle iron guide part 3 is a part of frame B and extends up and attaches to rod N and is spaced wide enough to slip freely on guide part 1.

55 I claim:

1. In combination in a dyeing machine, a tank, a shaft rotatably mounted on said tank, means for rotating said shaft, eccentrics mounted at each end of said shaft, hangers secured to and depending from said

eccentrics, a yarn carrying frame pivotally suspended from said hangers and adapted to submerge the yarn in the liquid with which the tank is filled during the vertical reciprocatory movement of said frame due to 70 the action of the eccentrics.

2. In combination in a dyeing machine, a tank open at its top, vertical bearing supporting columns one at each end of said tank, bearings in the top of said columns 75 for receiving the ends of a rotatable shaft, means for rotating said shaft, eccentrics mounted one at each end of said shaft, hangers secured to and operated upon by said eccentrics, a yarn carrying frame pivotally suspended from said hangers, guide means between the frame and tank, said frame having an upper set of spaced slotted bearings for yarn supporting rolls and a lower set of correspondingly spaced slotted 80 bearings for rolls, an upper set of rolls in said upper bearings, and a lower set of rolls in said lower bearings, said upper rolls at one end having ratchet driving means, a stationary rod depending from said shaft, guide 85 means between said rod and the adjacent hanger, and link means connecting said rod with said ratchet means to impart intermittent motion to said rolls upon relative movement between the frame and stationary rod 90 due to the eccentric connection of the shaft to the frame.

3. Apparatus according to claim 2 in which said link means and ratchet driving means comprise a cross-head on the stationary rod, links depending from each side thereof, horizontally disposed rods slidable in the frame and pivotally connected to said links, said rods being movable in opposite directions and having depending pawl members, toothed drive wheels secured to the ends of the upper rolls and operable by said pawl members upon outward movement of said rods by spring pressed detents on said pawls adapted to engage the teeth of 105 the drive wheels.

4. Apparatus according to claim 2 in which said link means and ratchet driving means comprise a cross-head on the stationary rod, links depending from each side thereof, horizontally disposed rods slidable in the frame and pivotally connected to said links, said rods being movable in opposite directions, pawl members pivotally mounted to said rods adjacent each roll and depending from said rods, each of said pawl members having an opening rotatably receiving the end of the corresponding roll, toothed drive wheels on said rolls having teeth outside of said pawl members, and spring pressed detents on the lower ends of said pawl members to engage the teeth of the drive wheels.

5. In combination in a dyeing machine, a tank open at its top, bearing supports at 130

- the opposite ends of said tank, a rotary drive shaft removably mounted in said supports, eccentrics mounted one at each end of said shaft, hangers secured to and operated upon by said eccentrics, a yarn carrying frame pivotally suspended from said hangers, yarn supporting rolls rotatably mounted in said frame, a stationary rod depending from said shaft, and means between the rod and frame for imparting intermittent rotary motion to said rolls upon relative movement between the frame and stationary rod. 5
6. In a dyeing machine, a tank open at its top to removably support a rotary drive shaft, eccentrics mounted on said shaft, a yarn carrying frame hung from said eccentrics, rolls rotatably mounted in said frame, a stationary rod depending from said shaft, and means between the rod and frame for 10
- imparting intermittent rotary motion to 20
said rolls upon relative vertical movement
between the frame and stationary rod due
to the shaft eccentrics operating upon the
frame. 15
7. Apparatus according to claim 6 in 25
which said means comprises toothed drive
wheels for said rolls, pawl members pivot-
ally carried on said rolls, spring pressed
pawls on one end of said pawl members to
cooperate with said teeth, a bar connecting 30
the opposite ends of said pawl members, and
a link connecting the bar with the said sta-
tionary rod to impart horizontal movement
to said rod and consequent rotary movement
to said rolls upon movement of said frame 35
relative to said rod. 20

In testimony whereof I affix my signature.
CHARLES EDWARD KIMBALL.
